US0D1065310S

(12) **United States Design Patent** (10) **Patent No.:** **US D1,065,310 S**
(45) **Date of Patent:** **** Mar. 4, 2025**

(54) **ARMLESS EYEWEAR**

(71) Applicant: **Ombraz Inc.**, Clyde Hill, WA (US)

(72) Inventors: **Jensen Brehm**, Kirkland, WA (US);
Nikolai Paloni, Boise, ID (US); **John Ohran**, West Linn, OR (US); **Greg Quist**, Seattle, WA (US)

(73) Assignee: **Ombraz, Inc.**, Clyde Hill, WA (US)

(**) Term: **15 Years**

(21) Appl. No.: **29/836,552**

(22) Filed: **Apr. 27, 2022**

Related U.S. Application Data

(63) Continuation-in-part of application No. 29/836,529, filed on Apr. 27, 2022, which is a continuation-in-part of application No. 17/722,342, filed on Apr. 16, 2022, and a continuation-in-part of application No. 29/777,153, filed on Apr. 2, 2021, now Pat. No. Des. 1,020,860, and a continuation-in-part of application No. 29/777,151, filed on Apr. 2, 2021, now Pat. No. Des. 1,020,859, which is a continuation-in-part of application No. 16/724,647, filed on Dec. 23, 2019, now Pat. No. 11,586,052, said application No. 29/777,153 is a continuation-in-part of application No. 16/724,647, filed on Dec. 23, 2019, now Pat. No. 11,586,052, said application No. 29/777,151 is a continuation-in-part of application No. 29/714,712, filed on Nov. 25, 2019, now Pat. No. Des. 926,867, said application No. 29/777,153 is a continuation-in-part of application No. 29/714,712, filed on Nov. 25, 2019, now Pat. No. Des. 926,867, which is a continuation of application No. (Continued)
